UNITED STATES PATENT OFFICE.

JOHN HENRY HYAMS, OF CHICAGO, ILLINOIS.

COLLAPSIBLE CLOTHES CABINET.

Application filed June 19, 1922. Serial No. 569,284.

To all whom it may concern:

Be it known that I, JOHN HENRY HYAMS, a citizen of the United States of America, and resident of the city of Chicago, in the 5 State of Illinois, United States of America, have invented certain new and useful Improvements in Collapsible Clothes Cabinets, of which the following is a specification.

This invention relates to collapsible 10 clothes cabinets, and has for its objects to provide an improved cabinet wherein means are adapted to receive clothes, and to provide a hat receptacle within the clothes cabinet.

Further objects are to provide an improved collapsible clothes cabinet comprising a casing pivotally mounted to a supporting board and a framework in the 15 casing carrying clothes hooks and rods, to provide a supporting arrangement carried by the board and casing and designed to retain the casing in right angular position relatively to the board, to provide a bracket designed to engage a U-shaped member on 20 the casing in order to support the cabinet on a vertical surface, such as a wall or other suitable supports.

A further object is to provide a means of attaching a curtain and drape around the 25 cabinet in order to enhance the appearance of the same.

Further objects are to provide an improved collapsible clothes cabinet that is simple in construction, not liable to go out 30 of repair, and generally to adapt the several parts to better perform the functions required of them.

With the above and other objects in view, the invention consists essentially of the improved construction hereinafter described 35 in detail in the accompanying specification and drawings.

In the drawings:

Figure 1 is a perspective view of the 40 improved clothes cabinet in working or unfolded position.

Figure 2 is a longitudinal section through the same.

Figure 3 is a section on the line 3—3 of 45 Figure 2.

Figure 4 is a fragmentary perspective view showing the framework inside the casing.

Figure 5 is a fragmentary perspective of 50 a portion of the frame showing the means of supporting the foldable legs.

Figure 6 is a fragmentary perspective of a portion of the hat box.

Figure 7 is a section on the line 7—7 of 55 Figure 3.

Figure 8 is a perspective view of the collapsible clothes cabinet in collapsed position.

Like characters of reference indicate corresponding parts in all the figures.

Referring to the drawings, A represents the improved cabinet comprising a supporting board 10 to which is pivotally mounted as at 11 a casing 12. Mounted in the casing is a framework 13 intermediate 60 of the length of which on each side are connected links 14, the opposite end of each which is adapted to be connected to a bolt 14^a carried by an anchoring post 15 on the board 10.

The bolts 14^a of the anchoring posts 15 carry supporting members 16 which support a clothes rod 17. The clothes rod 17 has its two ends formed with pintles 18 designed to engage holes formed at the ends 65 of two supporting brackets 19 and 20, which are pivotally secured to the framework 13. The board 10 carries a shoulder 21 on which is mounted the bottom 22 of a hat box 23. Other members 24 and 25 are provided on 70 the board 10 being located at right angles to the shoulder 21 and to which members are hingedly connected the two sides or flaps 26 and 27 of the hat box.

The member 25 is larger than the member 75 24 so that the hinged point of the flap 26 is lower than the hinged point of the flap 27. By means of this arrangement when the flap 26 is folded down, the flap 27 may be folded down on top of the flap 26. In 80 like manner the shoulder 21 is thicker than the member 25 and the bottom 22 of the hat box may be folded on top of the flap 27, when the cabinet is to be collapsed.

The board 10 is provided at its upper 85 end with a U-shaped element 28 designed to engage two fingers 29 and 30 carried by a bracket 31, which can be secured to a wall or other vertical support.

The top of the casing 12 is formed with 90 a flange 32 in which a plurality of hooks 33 are provided and the hooks 33 are designed to engage with button holes formed on the edge of two curtains 34 and 35 which are designed to join in the rear and be 95 buttoned together or otherwise secured.

The opposite ends of the curtains 35 ex-

- tend towards the front of the cabinet and are hemmed as at 36 in order to engage a rod or pole 37, which has a squared end 38, and a pintle formed on its opposite end.
- 6 The pintle is designed to engage a hole in the forward end of the framework 13, while the squared end 38 is adapted to be engaged by a notch 39 also formed in the framework 13 at the forward end thereof.
- 10 By means of this arrangement it is obvious that the two front portions of the curtains 34 and 35 may be slid on the rod or pole 37 so that access may be had underneath the casing into the cabinet.
- 15 The framework 13 carries a plurality of hooks designed to receive clothes, and it is obvious that any number of these hooks may be provided extending inwardly of the framework 13.
- 20 In order to enhance the appearance of the cabinet, a drape 40 may be provided at the top end of the cabinet and formed with button holes designed to engage the hooks 33 on the flange 32 of the casing.
- 25 The rear ends of the drape 40 are secured to a lace 41, the two ends of which lace may be tied as at 42 after the casing has been set up. The lower end of the board 10 is equipped with a pair of set screws 43, the ends of which are designed to bear against the wall or other supporting member for the casing in order to position the board 10 parallel to the wall.
- When this improved collapsible clothes cabinet is to be put up, the casing A as shown at Figure 8 is placed with the board downwardly, and the casing being pivoted on its hinge is brought at right angles to the board. The arms or links 14 are then brought down and engaged with the bolts 14^a. The clothes rod 17 is then turned into normal position, and its end pintles 18 are brought into engagement with the retaining members 19 and 20.
- 35 The hat box 23 is then formed by unfolding the bottom 22 and the flaps 27 and 28 which are then secured together by means of suitable hooks 44 carried by the bottom 22 and engaging the pegs 45 provided on the flaps 26 and 27. The folding legs 46 which are pivoted to the inside of the casing as at 47 are then pivoted downwardly in order to support the casing which is then turned up in the position shown in Figure 4.
- 40 The curtain 34 is then engaged with the hooks at the top of the casing after which the curtain 35 is similarly engaged with the hooks on the opposite side of the flanged top of the casing, and the rear ends of the curtains 34 and 35 are buttoned together at the rear of the casing.
- 45 The curtain rod 36 is then brought down and engaged with the hemmed portions of the curtains 34 and 35 after which the rod
- 50 is returned into engagement with the forward end of the framework 13, the squared end of the pole or rod being engaged by the notch 39 of the framework.
- 55 The drape 40 is then secured on top of the curtains 34 and 35, and retained in position through the lace 41 being knotted as at 42. The cabinet is then raised on the bracket 31 by bringing its U-shaped element 28 into engagement with the fingers 29 and 30 of the bracket 31.
- 60 The foldable legs 46 which are not now useful for any purpose, are folded back into position and retained against the framework 13 by means of straps 48 which are carried by the framework and may be provided with studs 49 or other fastening device. The cabinet is then in set position to be used, and the same may be straightened up by means of the adjustment screws 43 which engage the wall or other support of the cabinet.
- 65 As many changes could be made in the above construction, and many apparently widely different embodiments of my invention, within the scope of the claim, constructed without departing from the spirit or scope thereof, it is intended that all matter contained in the accompanying specification and drawings shall be interpreted as illustrative and not in a limiting sense.
- 70 What I claim as my invention is:
- 75 A collapsible clothes cabinet comprising a back board, a casing pivotally secured to the back board, a suitable frame within the casing, supporting links pivotally secured intermediate of the casing and similarly secured at their other ends to anchoring posts on the back board, supporting links pivotally secured with the first links on the casing, and adapted to support a clothes rod, cross supporting links pivotally engaging the clothes rod and the anchoring post, a shoulder intermediate of the back board, a shelf hingedly mounted on said shoulder, a pair of vertical members mounted on the back board above and coinciding with the ends of said shoulder, side walls hingedly attached to the vertical members designed to form a hat receptacle, foldable auxiliary supporting legs pivotally mounted on the casing, means for holding said legs in collapsed position, a U-shaped auxiliary suspending member for the casing, a plurality of hook members around the top of the casing, a curtain for said device, a plurality of orifices in the curtain designed to engage with said hooks, and means to hold the device from a wall or the like.
- 80 In witness whereof I have hereunto set my hand in the presence of two witnesses.
- JOHN HENRY HYAMS.
- Witnesses:
- CHARLES A. GRIFFIN,
A. H. ALFORD.
